UNITED STATES PATENT OFFICE.

JOSEPH KEENE, OF CHICAGO, ILLINOIS.

SPRING-HINGE.

SPECIFICATION forming part of Letters Patent No. 620,933, dated March 14, 1899.

Application filed October 29, 1898. Serial No. 694,923. (No model.)

To all whom it may concern:

Be it known that I, JOSEPH KEENE, a resident of the city of Chicago, in the county of Cook and State of Illinois, have invented certain new and useful Improvements in Spring-Hinges, of which I do declare the following to be a full, clear, and exact description.

The present invention has for its main object to enable a light, cheap, durable, and effective construction of hinge to be made from plate metal, preferably sheet-steel.

A further object of the invention is to improve the spring-hinge in various details of construction; and the invention consists in the features of improvement hereinafter described, illustrated in the accompanying drawings, and particularly pointed out in the claims at the end of this specification.

Figure 1 is a view in elevation of a double-acting spring-hinge embodying my invention. Fig. 2 is a plan view with the pintle-nuts removed, the pintles being shown in section. Fig. 3 is a perspective view showing a partially-shaped blank from which the spring-barrels and connecting-web are formed. Fig. 4 is a perspective view showing the blank illustrated in Fig. 3 further folded. Fig. 5 is a perspective view showing the completed spring-barrels and connecting-web. Fig. 6 is a perspective view of the reinforce-plate. Fig. 7 is an inverted perspective view of the reinforce-plate. Fig. 8 is a view in central vertical longitudinal section through the reinforce-plate. Fig. 9 is a view in central vertical section through one of the spring-barrels shown in Fig. 1. Fig. 10 is a detail perspective view of one of the bearing-washers. Fig. 11 is an inverted plan view of the pintle-nut.

In the accompanying drawings my invention is shown as applied to a double-acting spring-hinge, because this is the preferable embodiment of my invention and the one for which the greatest trade demand exists. It is manifest, however, that without departure from the broad scope of the invention features of it may be embodied in a single-acting spring-hinge—that is to say, in a hinge in which but a single spring-barrel is employed.

In the preferred practice of my invention

a plate of metal (usually sheet-steel) of proper thickness and dimensions is first subjected to the action of dies in order to give to the blank the general outline shown in Fig. 3 of 55 the drawings. This blank is then by means of suitable dies brought first to the shape shown in Fig. 4 and subsequently to the finished shape shown in Fig. 5 of the drawings. By this means I am enabled to produce from 60 a single blank the web A and the spring-barrels B and B'. Preferably, although not essentially, the top and bottom edges of the barrels B and B' are formed with the countersunk portions b, over which will set the cylindrical portions c of the reinforce-plates C. It has heretofore been proposed to manufacture the barrels and connecting-web of a double-acting spring-hinge from sheet-steel; but in order to give the proper strength to 65 the web it has been deemed necessary to form the web of a plurality of plates or thicknesses riveted together. This construction is seriously defective for the reason that while the required strength is imparted to the web still 70 the points of connection between the web and the barrels at the sides thereof are not materially strengthened and in fact have little, if any, more strength than the single thickness of metal of which the barrels are formed. In 75 practice it is found that a great part of the strain to which the hinge is subjected is exerted at the point of union of the spring-barrels and the connecting-web, and the serious desideratum is to afford some simple and effective means for giving the required strength at such points, as well as to the web, without materially increasing the weight of the parts or the cost of the hinge. By the present invention I am enabled to form the barrels and connecting-web of a double-acting 80 spring-hinge of uniform thickness and to so strengthen these parts by reinforce-plates as to give to the hinge far greater strength and durability than has been attainable by prior 85 constructions.

A reinforce-plate C is preferably attached to both the top and bottom of the spring-barrels and their connecting-web. Each of these reinforce-plates is by preference formed from 90 a blank of sheet-steel swaged by suitable dies to the shape shown in Figs. 6, 7, and 8 of the

drawings—that is to say, the reinforce-plate has its central portion of channel shape in cross-section, and at the ends of the channel formed by this central portion of the plate are 5 the cylindrical parts c , that set over the ends of the spring-barrels B and B' , while the channel-shaped body of the plate C fits over the edge of the web A . Preferably the body or central portion of each of the reinforce-plates 10 C is extended in offset relation to the cylindrical ends c and c' , the outer portions of which are by preference formed of inwardly-turned flanges c^2 , adapted to cover the edges of the spring-barrels B and B' when the reinforce-plates C are in position thereon. In 15 practice I have found that the reinforce-plates C serve most effectively to strengthen the web A and the points of union between the web and the spring-barrels B and B' , so that all 20 danger of breakage of the parts is avoided, and this, too, without adding considerably to the weight of the parts or their cost. I prefer that the reinforce-plate C should be made from a single plate of metal with its central 25 portion and end portions shaped as shown, because this construction I believe to be most effective, although manifestly a reinforce-plate varying somewhat from the construction illustrated might be made without de- 30 parting from the broad spirit of the invention.

When the spring-barrels and web have been brought to the shape shown in Fig. 5, a reinforce-plate C will be placed over the top and bottom edges of the web and over the corresponding ends of the spring-barrels, as shown 35 in Fig. 1 of the drawings. Through each of the barrels B and B' extends a pintle D , having a head d at one end and having its opposite end screw-threaded to receive a correspondingly-threaded nut d' . The pintle D passes through the caps e of the hinge-leaves E and E' , these caps being shown as formed of conoidal outline from sheet-metal extensions of the leaves E and E' , that are also 40 formed of sheet metal. Within the caps e are preferably set the plates or disks f , through which the pintle D passes, and upon the bottom cap rests a stationary spring-holder G , within the slot g of which is fastened the lower 45 end of the coiled torsion-spring H . The upper portion of the pintle D passes through the movable spring-holder G' , with the grooved stem of which engages the upper end of the coiled spring H . The spring-holder G' is 50 formed about its periphery with a series of pin-holes g' , adapted to receive a pin g^2 for the purpose of holding the spring under tension in manner well understood by those familiar with this class of devices. Within the 55 upper end of each of the barrels B and B' is preferably set a bearing sleeve or collar K , the flange k of which sets over the upper part of the cylindrical portion c of the reinforce-plate C . The upper face of the collar K affords 60 a broad bearing for the head of the spring-holder G' , which turns under the swinging 65

movements of the hinge. It is advantageous to employ a broad bearing-sleeve K , because by this means the wear upon the parts is very materially lessened. It will be observed by 70 reference to Fig. 9 of the drawings that there is no bearing sleeve or collar encircling the spring-holder G at the lower end of each of the barrels B and B' , since this spring-holder, being stationary, needs no bearing sleeve or 75 collar; but, by preference, the inwardly-turned flange c^2 of the lower reinforce-plate C is made somewhat broader than the corresponding flange c^2 of the upper reinforce-plate in order to more snugly inclose the stem 80 of the spring-holder G .

In order to prevent the accidental working loose of the pintle D , I provide suitable interlocking lugs and seats between the pintle-nut and preferably also between the pintle-head and the adjacent parts. As shown, this feature of my invention is practiced by forming both the upper and lower caps e with lugs e^2 , adapted to enter corresponding seats e^4 , formed upon the inner faces of the heads d 90 and nuts d' of the pintle. It will therefore be seen that when the pintle D is placed in position, as shown in Figs. 1 and 9 of the drawings, and when the nuts d' are forced downward upon the caps e the heads d of 95 the pintles will be drawn upwardly against the adjacent cap e . The lug e^2 of the cap e will enter the notches e^4 ; but I have found in practice that the elasticity of the material of which the caps e are formed permits the nut d' and head d of the pintle to be turned some 100 distance after the initial bearing upon the lugs d^2 , thereby causing the lugs d^2 to snap into the seat e^4 and so retain the pintle against all danger of accidental movement or working 105 loose of the parts.

By reference to Figs. 6 and 8 of the drawings it will be seen that the flanges c^2 of the reinforce-plate C are formed with notches c^3 , the notches of the upper reinforce-plate serving to receive corresponding offsets k' , that project from the bearing sleeves or collars K , while the notches c^3 of the lower reinforce-plate receive offsets k^2 , projecting from the 110 stem of the stationary spring-holder G . 115

Manifestly the details of construction above set out may be varied without departure from the spirit of the invention and features of the invention may be employed without its adoption as an entirety. 120

Having thus described my invention, what I claim as new, and desire to secure by Letters Patent, is—

1. A spring-hinge having a barrel and a web formed integral from a plate of metal and a reinforce-plate formed separate from said web and barrel and extending around said barrel and upon opposite sides of said web. 125

2. A double-acting spring-hinge comprising a web, a barrel at each side of said web and a reinforce-plate formed separate from the web and barrels and extending around 130

both barrels and upon opposite sides of said web.

3. A double-acting spring-hinge comprising a web, a barrel at each side of said web and a reinforce-plate formed separate from the web and having the central channel-shaped portion setting over the edge of the web and cylindrical end portions encircling said barrels.
- 10 4. A double-acting spring-hinge comprising a web, a barrel at each side of said web and a reinforce-plate formed separate from the web and barrels, said reinforce-plate consisting of a cap having a channel-shaped central portion inclosing the ends of the web and cylindrical portions encircling the ends of the

barrels, said cylindrical portions being formed with inwardly-extending flanges to set over the ends of the barrels.

5. In a spring-hinge the combination with the pintle having a head and with its retaining-nut and with suitable caps or parts adjacent said head and nut, of interlocking seats and lugs intermediate the pintle-cap and the nut, and the parts with which they engage, whereby the pintle is held against displacement.
